UNITED STATES PATENT OFFICE.

HARRY R. BIRELY, OF OSHKOSH, WISCONSIN.

DESIGN FOR A SPOON.

SPECIFICATION forming part of Design No. 21,153, dated November 3, 1891.

Application filed October 6, 1891. Serial No. 407,945. Term of patent 3½ years.

To all whom it may concern:

Be it known that I, HARRY R. BIRELY, a citizen of the United States, residing in Oshkosh, in the county of Winnebago, State of Wisconsin, have invented and produced a new and original Design for Spoons, of which the following is a specification, reference being had to the accompanying drawing, forming part thereof.

10 The figure is a plan view of a spoon, showing the design upon the handle.

My invention is for "souvenir-spoons" so called; and the leading feature of my design consists in a bas-relief of an Indian upon the spoon, placed within the outline of the same. In connection with the design I contemplate adding the descriptive words "Chief Oshkosh;" but such words form no part of my design. The Indian is represented as wearing

a hat instead of the usual plumage, and directly beneath the Indian a shield, quiver, gun, and pipe are shown, which add to the characteristic features of the design; but the same are only minor features of my design. I have also shown the spoon truncated at its 25 handle end to give it a symmetrical appearance with the flat top of the hat worn by the Indian.

What I claim is—

The design for spoons, substantially as 30 herein shown and described.

In testimony whereof I affix my signature in presence of two witnesses.

HARRY R. BIRELY.

Witnesses:

EDWIN CLIFFORD,
FRED BEGLINGER.
